UNITED STATES PATENT OFFICE.

HAROLD H. SPANG, OF LEECHBURG, PENNSYLVANIA.

SHEET-METAL-CUTTING MACHINE.

1,314,286.

Specification of Letters Patent. Patented Aug. 26, 1919.

Application filed July 5, 1918. Serial No. 243,412.

To all whom it may concern:

Be it known that I, HAROLD H. SPANG, a citizen of the United States, residing at Leechburg, in the county of Armstrong and State of Pennsylvania, have invented certain new and useful Improvements in Sheet-Metal-Cutting Machines; and I do hereby declare the following to be a full, clear, and exact description of the invention, such as will enable others skilled in the art to which it appertains to make and use the same.

This invention has for its object to provide an improved and simplified cutting machine, whereby large sheets of sheet metal or other material may be expeditiously cut into strips of any desired length and width.

With this and other objects in view, the invention consists in the construction and novel combination of parts hereinafter fully described, illustrated in the accompanying drawings and pointed out in the claims hereto appended; it being understood that various changes in the form, proportion, size and minor details of construction, within the scope of the claims, may be resorted to without departing from the spirit or sacrificing any of the advantages of the invention.

In the drawings:

Figure 1 represents a side elevation of the cutting machine, partly in section.

Fig. 2 represents a top plan view thereof.

Fig. 3 represents a detail sectional view on the line 3—3 of Fig. 1.

Fig. 4 is a similar view on the line 4—4 of Fig. 1.

Fig. 5 is a detail side elevation of the feeder and cutter roll driving gears, and

Fig. 6 represents a detail transverse sectional view through one of the cutting rolls.

Referring to the drawings in detail, wherein similar reference numerals designate corresponding parts throughout the several views, the numeral 10 designates generally the supporting frame structure for the machine which includes the end supporting legs 11 and intermediate legs 12. The legs at one end of the frame structure are connected with the intermediate legs 12 by the parallel side members 13, provided with slots 13' receiving the reduced ends 14 of the slats or boards 15 forming a table having a series of transversely extending slots to accommodate the cutting knives which will be hereinafter more fully described. The slats are held in position in the frame

structure by nuts 16 and are designed to support the sheet of metal or other material as the latter is cut to the desired length. It will be apparent that the slats or boards are adjustable in the slot 13'.

A drive shaft 17 is journaled in bearings provided in the legs 11 and 12 and is connected with a crank shaft 19 by a train of gears 20. The crank shaft 19 is also journaled in the legs 11 and 12 and is provided with two or any other desired number of crank pins or arms 21 having connection with rods 22 attached to a reciprocable shaft 23. The shaft is designed for reciprocation in an inclined plane in guide slots 24 provided in the supporting legs 11 and 12 and is connected by the rods 25 with the outer terminals of relatively movable cutting knives 26, as indicated at 27. The rods 25 are mounted for adjustment longitudinally of the shaft 23, and the blades are pivotally supported at their outer ends for adjustment toward and away from each other by a shaft 28 extending between the legs 11 and 12 and arranged directly above one of the side members 13. Connecting the blades 26 is a rod 26' adapted to prevent a lateral movement or play in the blades 26. As will be readily understood, the rod 26', which may be detachably secured to the blades 26 in any suitable or preferred manner, is removed during adjustment of the blades toward or away from each other, this rod being replaced after the desired adjustment has been effected and secured in position in any well known manner.

The relatively movable blades 26 are arranged for movement through the slots between the slats 15 and coöperate with relatively stationary blades 28^a supported at one end on a shaft 29 extending between the supporting legs and connected at their opposite terminals with inclined braces 30 connected with a supporting rod 31 extending between the legs. While blades 28^a are stationary relative to blades 26, it will be understood, of course, that they are adjustable toward and away from each other upon the rod 31 and shaft 29 so as to accommodate adjustment of the upper blades. The blades 26 and 28^a are, of course, secured in proper adjustment upon their supporting shafts or rods by means of set screws, as illustrated in Fig. 3 of the drawings, or by any other suitable equivalent means.

During the rotary movement of the crank

shaft 19, the rod 23 is reciprocated in the guide slots 24 and the movable blades 26 are oscillated upon the shaft 28 and coact with the relatively stationary blades 28^a to cut 5 the sheet of metal or other material to the desired length.

The legs 11 at the opposite end of the supporting frame structure 10 are connected with the intermediate legs 12 by superimposed bearing beams 33 and 34, the lower beam 33 rotatably supporting a series of spaced parallel feed or cutter rollers 35 and the upper bearing members 34 supporting a duplicate series of superposed feed rollers 15 35. At the center of the series of cutter 20 rollers 35, a pair of superposed cutting rollers 36 are arranged and the rolls 36 are provided with circular cutting knives 37 arranged in pairs and designed to cut the sheet of metal into strips, as it is fed between the cutter or feed rollers 35.

The spindles of the several feed rollers 35 support intermeshing gear wheels 38 and the rotary movement of one gear wheel of 25 one pair is transmitted to the gear wheel of the adjacent pair by an intermediate or idler gear wheel 39 which is supported in a bearing 40 attached to the roll spindles and meshes with relatively small pinions 41 carried by the respective roll spindles.

Each of the cutting rolls 36 is provided with a flat surface 42 and the central aperture in the adjustable cutting blades 37 is shaped correspondingly so as to prevent rotary movement of the blades upon the rollers. The blades are held in adjusted position by set screws 43 which are fitted in internally screw threaded apertures in laterally projecting ears 44 carried by the 40 blades and abut the flat surface 42 of the rolls.

The spindle of the lower cutting roller 36 is connected with a relatively small pinion 45 which is connected by a train of gears 46 with the adjacent gear wheel 38 of the cutter and feed rollers 35 at one side of the cutting rolls 36, whereby the lower roller is driven during the operation of the machine. The upper cutting roller is 50 connected by a similar chain of gears with the series of cutter and feed rollers 35 on the opposite side of the cutting rolls.

The feed rollers at the opposite ends of the series are connected by a train of gears 55 47, whereby the rolls are driven during the operation of the machine.

What I claim is:

1. A cutting machine comprising a frame structure including spaced side members, 60 spaced slats supported by the side members, a relatively stationary knife arranged between the slats, a shaft journaled in the frame structure, a crank pin carried by said shaft, a reciprocable shaft, means connecting the crank pin of the first mentioned

shaft with the reciprocable shaft, a pivoted blade adapted to coöperate with the relatively stationary blade, and means connecting the reciprocable shaft with said pivoted blade. 70

2. In a machine of the character described, a supporting frame, feeding and cutting mechanisms carried by said frame for feeding a sheet of material to be operated upon longitudinally thereof and cutting this material into parallel strips during its passage through said mechanisms, a receiving table positioned to receive strips of material fed over the same from the cutting and feeding mechanisms, said table being provided with a plurality of spaced parallel slots extending at right angles to the direction of movement of the strips of material, spaced pairs of cutting shears positioned adjacent the table and operable through said slots for cutting the strips of material into predetermined lengths, said pairs of shears being mounted for adjustment toward and away from each other so as to cut the strips of material into different lengths, and means for operating said shears. 90

3. In a machine of the character described, a supporting frame, feeding and cutting mechanisms carried by said frame for feeding a sheet of material to be operated upon longitudinally thereof and for cutting this material into parallel strips during its passage through said mechanisms, a receiving table supported by the 100 frame adjacent the inner ends of said feeding and cutting mechanisms for receiving the strips of material cut, said receiving table being provided with a plurality of spaced parallel slots disposed at right angles to the direction of movement of said strips fed across the table from the feeding and cutting mechanisms, spaced pairs of shears supported by the frame and operable through the slots of said table for cutting the strips of material into predetermined lengths, said pairs of shears being adjustable toward and away from each other so as to vary the length of the strips cut, and means for operating said shears simultaneously with the operation of the cutting and feeding mechanisms. 110

4. In a machine of the character described, a supporting frame, feeding and cutting mechanisms adapted to feed a sheet 120 of material to be operated upon longitudinally of said frame and to cut said sheet into a plurality of parallel strips longitudinally thereof, a receiving table positioned adjacent said feeding and cutting mechanisms so as to have the strips produced thereby passed over said table, the table being provided with a plurality of transverse parallel slots disposed at right angles to the direction of travel of said strips, a 130

plurality of cutting blades supported by the frame beneath the table and adjustable toward and away from each other so as to be positioned adjacent any of the slots of 5 the table selectively, a plurality of cutting blades pivotally supported by the frame above the table so as to be movable toward and away from said lower blades, the lower blades being held against movement and 10 coöoperating with said upper blades to produce shears for cutting the strips of material, said upper blades being mounted for adjustment toward and away from each other, and means for operating said upper 15 blades.

5. In a machine of the character described, a supporting frame, feeding and cutting mechanisms carried by said frame for feeding a sheet of material to be operated upon longitudinally thereof and for cutting this sheet into parallel strips extending longitudinally of the sheet, a receiving table composed of a plurality of spaced slats supported by the frame and 20 positioned to receive the strips of material fed over the same from said feeding and cutting mechanisms, said slats being disposed transversely of the frame, spaced cutting blades rigidly supported in substan- 25

tial horizontal position beneath the slats 30 of the table, said blades being mounted for adjustment toward and away from each other so as to have the distance between the blades varied and so as to be brought into alinement with any of the spaces between 35 said slats selectively, the slats being adjustable toward and away from each other so as to permit accurate adjustment between the slats and blades, a supporting shaft carried by the frame above said slats 40 and extending longitudinally thereof, blades rockably mounted on said shaft adjacent their outer ends so as to be adjustable longitudinally thereof toward and away from each other, said rockable blades coöper- 45 ating with the blades beneath the slats of the table to provide cutting shears for cutting the strips of material passed across said table into lengths, and means for operating said rockable blades simultaneously 50 with the operation of the said feeding and cutting mechanisms.

In testimony whereof I affix my signature in presence of two witnesses.

HAROLD H. SPANG.
